UNITED STATES PATENT OFFICE

2,602,000

CHARGING BUCKET

John N. Richardson, Port Washington, Wis., assignor to Modern Equipment Company, Port Washington, Wis., a corporation of Wisconsin

Application January 31, 1948, Serial No. 5,644

12 Claims. (Cl. 294—69)

1

This invention relates to improvements in charging buckets. In foundries it is common practice to utilize cylindrical buckets having vertically movable bell-shaped bottoms for the purpose of delivering a charge of pig iron, coke and lime into a cupola. These buckets are commonly moved into the door or receiving opening of the cupola by means of a skip-carriage or by an overhead carrier, there being mechanism in connection with each type of transporting device for moving the bucket into discharge position and for then discharging the contents by mechanically lowering the bell-shaped bottom. With the large bell type of bottom commonly used, all of the charge must fall outwardly of the periphery of the bucket with the result that the charge is thrown against the sides of the cupola, and then bounces back toward the center. Furthermore, due to this method of discharge there must be substantial clearance between the periphery of the bucket and the sides of the cupola lining, otherwise there is insufficient room for the charge to fall downwardly.

In melting iron in a cupola, coke is placed in the bottom to extend some distance above the tuyères and each succeeding layer of iron is accompanied by a layer of coke in order to maintain the bed at this proper melting height. In large cupolas where iron and coke are solidly packed in the center of the cupola and loose near the outside wall, the entering air will pass up the sides of the cupola because this is the path of least resistance due to the loose packing. This causes poor combustion at the center of the cupola and chilling of the falling slag. Such chilled slag eventually blocks up the tuyères and may entirely stop the melting operation after a sufficient period of time. It is thus apparent that it is desirable to maintain a looseness near the center of the cupola and prevent a loose condition near the side wall.

It is a general object of the present invention to provide an improved charging bucket having a novel bottom construction which provides for efficient distribution of the charge with a loose portion in the center of the cupola.

A further object of the invention is to provide a charging bucket having side wall portions which are of novel shape and having a fixed bottom portion of relatively small diameter, the side wall portions being segmental and hinged at their upper edges for movement into and out of closing relationship with respect to said fixed bottom portion.

A more specific object of the invention is to

2

provide a construction as above described in which the fixed bottom portion is in the form of a bell of substantially less diameter than the diameter of the top opening of the bucket, the shape of the bell tending to direct some of the material outwardly, and the lower portions of the swingable side walls being adapted to direct part of the material downwardly along the side wall of the cupola. Thus, the small bell and swingable sides cause the charge to be deposited in the cupola with a looseness at the center, there being little bouncing from the sides as occurs with the conventional bell-bottom bucket and therefore no dense packing at the center.

15 A further object of the invention is to provide a bucket construction as above described wherein there is a bucket latch which is controlled by a top horizontally projecting lever and wherein there is an enclosure for said lever extending transversely of the bucket opening.

With the above and other objects in view, the invention consists of the improved charging bucket, and all its parts and combinations, as set forth in the claims, and all equivalents thereof.

25 In the accompanying drawing illustrating one complete embodiment of the preferred form of the invention, in which the same reference numerals designate the same parts in all of the views:

30 Fig. 1 is a top view of the improved charging bucket; and

Fig. 2 is a sectional view taken along the line 2—2 of Fig. 1.

Referring more particularly to the drawing, the bucket includes a supporting band 5 having its upper edge welded or otherwise secured as at 6 to the inner circular edge portion of a flat ring 7. A flared rim portion 8 has its lower edge welded or otherwise secured to the top of the ring 7 as at 9. The band 5, ring 7, and rim 8 form a surrounding supporting member.

Extending diametrically across the flared rim portion of the bucket is a horizontal elongated housing 10 which is preferably square in cross-section and preferably formed of two channels 11 and 12 welded together with their open sides facing each other.

Welded to the bottom of the elongated housing 10 midway of the length thereof is the upper end of a tube 13. The upper end of the tube communicates with the interior of the elongated housing 10 by way of an opening 14 in the bottom thereof. The connection between the upper end of the tube 13 and the housing may 55 be strengthened by means of triangular rein-

forcing plates or brackets 15 which are welded or otherwise secured to the bottom of the elongated housing and to the sides of the tube 13.

An inverted hollow conical member 16 having a maximum diameter which is substantially less than the diameter of the band 5 is provided with an upwardly projecting tubular stem 17 which fits within the lower end of the tube 13 and is welded in position as at 18 and 19. The member 16 forms a fixed, relatively small bottom bell.

A latch supporting rod 20 is guided for slideable movement in the tubular stem portion 17 of the bell 16. The rod 20 extends upwardly through the tube 13 and has its extreme upper end projecting into the elongated housing 10 at the top of the bucket. In this location it fits within the depending socket portion of a clevis 21 and the clevis, in turn, is pivotally connected as at 22 to the inner end of a lever 23. The latter is pivoted within the housing 10 on a pin 24 and has its outer end projecting through an opening 25 in the flared rim 8, the said outer end of the lever being provided with a knob or enlargement 26 which is normally maintained in the full line position of Fig. 2 by a trip lever 27. The latter is pivoted as at 28 to the outer end of a laterally projecting bracket 29. The lower portion of the trip lever is enlarged as at 30 and adapted for impingement against an abutment on the cupola lining to cause rocking of the trip lever to the dot and dash line position of Fig. 2 and release of the lever 23.

The lower end of the latch rod 20 extends through a central opening 31 in a latching spider 32, there being a nut 33 threaded on the lower end of the rod 20 to maintain the spider in position. The spider is provided with a plurality of laterally projecting arms 34, each having an upwardly bent flange 35 at its outer end having an inclined inner face 36.

Hinged at their upper edges as at 37 to the lower portion of the band 5 are a plurality of segments 38 forming the sides of the bucket. In the preferred embodiment of the invention illustrated there are six of such segments and in the preferred embodiment each segment includes a flat upper portion 39 and a flat lower portion 39' which extends at an obtuse angle with respect to the upper portion 39. It is preferred, also, that when the sides are in the closed position shown in full lines in Fig. 2, that the upper portions 39 angle downwardly and outwardly. The objects of the invention may be accomplished by having a greater or lesser number of side forming segments, and said segments may be of any selected form in cross-section. It is important, however, that the segments have lower portions such as the portions 39' which angle or curve downwardly and inwardly as shown in Fig. 2. The side edges of the segments substantially abut along the lines 42 when the segments are in closed position.

It is preferred to have the lower edges of the segments provided with external strips of suitable material as at 40 to provide locking seats shaped for coaction with the tapered faces 36 of the flanges of the spider arms 34, there being one spider arm for each segment. It is further to be noted that the portion of the inverted cone 16 against which the lower edges of the segments seat is hexagonal and formed of straight edges 41 which angle downwardly and inwardly and which edges are each of the same length as the width of the segment part which contacts it.

In use of the improved charging bucket, after the bucket has been moved into the opening of a

cupola by means of its carrier, a suitable abutment on the wall of the cupola will engage the enlargement 30 of the trip lever 27 to trip the lever from the full line position of Fig. 2 to the dot and dash line position therein. This will release the lever 23. As soon as this has been accomplished the weight of the spider 32 will cause it to move downwardly to the dot and dash line position of Fig. 2 releasing the lower edges of the door segments 30. The weight of the material in the bucket will then cause the segments 38 to swing on their hinges 37 to an open position as indicated by the dot and dash lines of Fig. 2. This permits the charge within the bucket to fall downwardly. Some of this charge will engage the inverted conical top of the bell 16 and be directed in an outward direction. Other material will be directed by the portions 39' of the side wall segments downwardly along the side wall of the cupola. The charge which engages the inverted conical top is directed outwardly just enough to keep the rest of the charge from falling toward the center. Thus, a relatively loose condition is maintained at the center of the cupola to provide a proper melting condition. The member 16 is relatively small in area so that the charge which is directed outwardly thereby does not hit the side walls in a manner to bounce back toward the center as occurs when the conventional full size bell bottom bucket is employed.

After the charge has been dropped the balance of the doors 38 is such that they tend to automatically swing by gravity back to a closed position.

It is to be noted that the elongated horizontal housing 10 protects the lever 23 from material as the material is being loaded into the bucket. In addition, the latch actuating rod 20 is protected by the vertical tube 13.

Various changes and modifications may be made without departing from the spirit of the invention, and all of such changes are contemplated, as may come within the scope of the claims.

What I claim as the invention is:

1. A cupola charging bucket comprising a surrounding supporting member, a centrally located bottom member, means connected to said supporting member for supporting said bottom member in a vertically fixed position spaced below the center of said supporting member, a segmental side closure having segments which are hinged adjacent their upper edges to said supporting member to form all side portions of the bucket and which have lower ends swingable from a closing position with relation to one another and against said fixed bottom member to an open position spaced laterally therefrom, and movable means mounted on said bucket and engageable with the lower end portions of said segments for releasably pressing said segments in closing position against said fixed bottom member.

2. A cupola charging bucket comprising a surrounding supporting member, a bottom member having an upper surface which slopes downwardly and outwardly from a central apex, means connected to said supporting member for supporting said bottom member in a vertically fixed position spaced below the center of said supporting member, a segmental side closure having segments which are hinged adjacent their upper edges to said supporting member and which have downwardly and inwardly inclined lower portions, the lower ends of said portions being swing-

able from a closing position with relation to each other and against said fixed bottom member to an open position wherein said lower ends are spaced laterally therefrom, and movably mounted means on said bucket for releaseably clamping said segments in closing position between said movably mounted means and said fixed bottom member.

3. A cupola charging bucket comprising a surrounding supporting member, a conical charge deflecting bottom member having an upper surface which slopes downwardly and outwardly from a central apex, means connected to said supporting member for supporting said bottom member in a vertically fixed position spaced below the center of said supporting member, a segmental side closure having segments which are hinged adjacent their upper edges to said supporting member and which have downwardly and inwardly inclined lower portions, the lower ends of said portions being swingable from a closing position with relation to each other and against said fixed bottom member to an open position wherein said lower ends are spaced laterally therefrom, and means mounted on said bucket and engageable with the lower end portions of said segments for releaseably latching said segments in closing position, said bottom member having a width equal to approximately one-half the width of said surrounding supporting member.

4. A cupola charging bucket comprising a surrounding supporting member, a bottom member, means connected to said supporting member for supporting said bottom member in a vertically fixed position spaced below the center of said supporting member, a segmental side closure having segments which are hinged adjacent their upper edges to said supporting member and which have downwardly and inwardly inclined lower portions, the lower ends of said portions being swingable from a closing position with relation to each other and against said fixed bottom member to an open position wherein said lower ends are spaced laterally therefrom, and movably mounted means on said bucket engageable with the lower end portions of said segments for releaseably pressing said segments in closing position against said fixed bottom member, the lower portions of said segments being shaped so that they are downwardly and inwardly inclined when in open position.

5. A cupola charging bucket comprising an annular supporting member, a conical bottom member, means connected to said supporting member for supporting said bottom member in a vertically fixed position spaced coaxially below the center of said supporting member, a segmental side closure having segments which are hinged adjacent their upper edges to said supporting member and which have downwardly and inwardly inclined lower portions, the lower ends of said portions being swingable from a closing position with relation to one another and against said fixed bottom member to an open position spaced laterally therefrom, and means on said bucket for releaseably latching said segments in closing position, the pivots of said segments being so located with respect to said conical bottom member that the segments automatically return by gravity to closed position against said bottom member.

6. A cupola charging bucket comprising a surrounding supporting member, a bottom member, means connected to said supporting member for supporting said bottom member in a fixed position spaced below the center of said supporting

member, a segmental side closure having segments which are hinged adjacent their upper edges to said supporting member and which have lower ends swingable from a closing position with

5 relation to one another and against said fixed bottom member to an open position spaced laterally therefrom, a latch for releaseably holding said segments in closed position, a rod projecting upwardly from said latch and slidably supported relative to said surrounding supporting member, a fulcrumed lever near the top of the bucket having an inner end pivotally connected to said latch rod and having a laterally projecting outer end, and a releaseable trip lever engageable with 10 said outer end of the lever.

7. A cupola charging bucket comprising a surrounding supporting member, an elongated member extending horizontally across said supporting member, an outwardly flared bottom member, means connected to said elongated horizontal member for supporting said flared bottom member in vertically fixed position below the center of said surrounding supporting member, a segmental side closure having segments which are 15 hinged to said supporting member and which have lower ends swingable from a closing position against said fixed bottom member to an open position spaced laterally therefrom, and movably mounted means on said bucket coacting with said bottom member for releaseably latching said segments in closing position.

8. A cupola charging bucket comprising a surrounding supporting member, an outwardly flared bottom member, means connected to said supporting member for supporting said outwardly flared bottom member in a vertically fixed position spaced below the center of said supporting member, a segmental side closure having segments which are hinged adjacent their upper edges to said supporting member and which have lower ends swingable from a closing position with relation to one another and against said fixed bottom member to an open position spaced laterally therefrom, a latch positioned below said bottom member, said latch being formed to releaseably hold said segments in closed position when the latch is in latching position, a rod projecting upwardly from said latch and slidably supported relative to said surrounding supporting member, and releaseable means for holding said rod and latch in raised latching position.

9. A cupola charging bucket comprising a surrounding supporting member, an outwardly flared bottom member, means connected to said supporting member for supporting said flared bottom member in a vertically fixed position spaced below the center of said supporting member, a segmental side closure having segments which are hinged adjacent their upper edges to said supporting member and which have lower ends swingable from a closing position with relation to one another and against said fixed bottom member to an open position spaced laterally therefrom, a latching spider positioned below said bottom member and having arms engageable with all of the segments when the spider is in latching position and when said segments are in closed position, a rod projecting upwardly from said latching spider and slidably supported relative to said surrounding supporting member, and releaseable means for holding said rod and latching spider in a raised latching position.

10. A cupola charging bucket comprising a surrounding supporting member, an outwardly flared bottom member, means including a vertical tube

depending from said supporting member for supporting said flared bottom member in a vertically fixed position below the center of said supporting member, a segmental side closure having segments which are hinged adjacent their upper edges to said supporting member and which have lower ends swingable from a closing position with relation to one another and against said fixed bottom member to an open position spaced laterally therefrom, a latch position below said bottom member for releaseably holding said segments in closed position, a rod slidably projecting upwardly from said latch through said bottom member and within said tube, and means near the top of the bucket for releaseably maintaining said rod and latch in a raised latching position.

11. A cupola charging bucket comprising a surrounding supporting member having a material receiving opening therein, a bottom member in the form of a cone, means connected to said supporting member for supporting said bottom member in a vertically fixed position spaced below the center of said supporting member, a segmental side closure having segments which are hinged adjacent their upper edges to said supporting member and which have lower portions inclined downwardly in a reverse direction from the inclined surface of the conical bottom member, the lower ends of said segment portions being swingable from a closing position with relation to each other and against a lower peripheral portion of said fixed bottom member to an open position wherein said lower ends are spaced laterally therefrom, and means for releaseably latching said segments in closing position.

12. A cupola charging bucket comprising a surrounding supporting member having a material receiving opening therein, an elongated hollow housing extending horizontally across said sup-

porting member, a bottom member, a tube depending from said elongated hollow housing and connected at its lower end to said bottom member to support the latter in fixed position below the center of said surrounding supporting member, a segmental side closure having segments which are hinged adjacent their upper ends to said supporting member and which have lower ends swingable from a closing position against said fixed bottom member to an open position spaced laterally therefrom, a latch located below said bottom member for releaseably latching said segments in closing position, an actuating rod for said latch extending slidably upwardly through said bottom member and within said tube and having its upper end projecting slidably into said elongated hollow member, a lever pivoted within said hollow member and having its inner end pivotally connected to the upper end of said rod and having its outer end projecting externally, and a releaseable external trip member positioned for releaseable engagement with the outer end of said lever.
